CLAIM

The ornamental design for capsule device, as shown and described.

DESCRIPTION

A portion of this patent document contains material which is subject to copyright protection. The copyright owner has no objection to the facsimile reproduction by anyone of the patent document or the patent disclosure, as it appears in the Patent and Trademark Office patent files or records, but otherwise reserves all copyrights whatsoever.

FIG. 1 is a perspective view of a capsule device according to an embodiment of the present design;

FIG. 2 is a front elevation view of the capsule device of FIG. 1;

FIG. 3 is a top plan view of the capsule device of FIG. 1;

FIG. 4 is a right side elevation view of the capsule device of FIG. 1;

FIG. 5 is a left side elevation view of the capsule device of FIG. 1;

FIG. 6 is a back elevation view of the capsule device of FIG. 1 (with lid to accessory inputs in closed position);

FIG. 7 is a bottom plan view of the capsule device of FIG. 1; and,

FIG. 8 is a perspective view of the capsule device of FIG. 1 (with lid to accessory inputs in open position).
